United States Patent Office

Des. 232,114
Patented July 16, 1974

232,114

TOY SPINNER

Eugene J. Echterling, Woodland Hills, Calif., assignor to
Questor Corporation, Toledo, Ohio

Filed Jan. 24, 1973, Ser. No. 326,489

Term of patent 14 years

Int. Cl. D21—01

U.S. Cl. D34—15 AH

FIG. 2

FIG. 3

FIG. 1

FIG. 1 is a perspective view of a toy spinner showing my new design;

FIG. 2 is a top plan view, the side opposite being substantially identical; and

FIG. 3 is a side elevational view.

I claim:

The ornamental design for a toy spinner, as shown and described.
